UNITED STATES PATENT OFFICE.

JOHN WILLIAM HESS, OF KITCHENER, ONTARIO, CANADA, ASSIGNOR TO CLUETT,
PEABODY & COMPANY, INC., OF TROY, NEW YORK, A CORPORATION OF NEW YORK.

FOLD-OVER COLLAR.

Application filed June 14, 1921. Serial No. 477,536.

My invention relates to fold-over collars of the soft type, to be worn either unstarched or very lightly starched, and has for its object the construction of such a 5 collar with few component parts of simple structure, economical to manufacture, but nevertheless possessing qualities which enable it to retain its desired shape and design, and particularly to hold its intended 10 fold along a predetermined line.

In the drawings hereto annexed, which illustrate my invention, Fig. 1 is a plan view of the outside of a fold-over collar, laid flat, and Fig. 2 is a cross section of the collar, at 15 and near the line of fold, on an enlarged scale.

The collar comprises, essentially, only three parts or members, namely the band B, top T and a juncture-covering tape C. The 20 band and top pieces are cut to shapes appropriate to their position in use from heavy, closely-woven fabric, and preferably of the same fabric, having greater body and stiffness than the similarly shaped pieces 25 heretofore usually employed in the manufacture of collars, and which are assembled to form tops and bands each composed of several layers of cloth. The fabric I employ may be variously woven, and is thick 30 enough and stiff enough to be inherently self sustaining, i. e., capable of standing without crumpling or wrinkling. When cut, as by dies, from the piece, the top and band members have edges from which ravelings inevitably project. In a finished collar these raw edges must be bound, hemmed, or otherwise rendered smooth and sightly. 35 Moreover, in order that a fold-over collar of this character shall hold its shape, though unstarched, it is necessary to make 40 sure that the fold will be formed in the top near the edge of the band. A preferred way to do this is to hold the edge of the band flat by some form of reinforcement 45 and thus permanently define the line along which the top folds and hangs from the band, and prevent the band from folding. By means of the structure and mode of assembling the several parts of the collar. 50 herein described, these desiderata are secured, with what I believe to be a minimum of collar-members and a minimum of manufacturing operations, assuming as a datum 55 that the top and band are to be originally distinct pieces.

The collar band B is bound, hemmed or, as shown, edge-turned all around its periphery. At and along the fold line, it is turned and creased at B¹, the edge part B² lying with the raw edge B³ against the body of the band. The collar top T is similarly edge-turned, making a fold-line at T¹. Along this fold line, the edge part T² of the collar top is overlaid upon the infolded edge part of the collar band. The raw edges of the turned margins of both top and band lie approximately in coincidence.

A covering tape C, a little wider than the turned margins of the top and band, is then overlaid upon the margin of the collar-top, and joined to the top and band by a line of stitching S¹, which passing through the tape C, collar top margin T² and two thicknesses of the band material, follows the contour of the designed fold line of the collar. The tape C, which slightly overlaps the raw edges of the turned margins of both top and band, is stitched to the body of the band B by a line of stitching S, which lies substantially parallel with the upper line of stitches S¹.

The turned margins of both top T and band B, along the peripheries of both parts, are elsewhere finished so as to secure and bind in the raw edges. Hems of any desired 85 fashion may be employed, or covering edge-tapes. I prefer, however, in the interest of simplicity, to bind in the turned margins with a zig-zag stitch, as indicated at D and D¹, these stitches lying on the inside of the top and band respectively. I do not herein claim this mode of finishing the edges of a collar, which is no part of my invention.

The four thicknesses of material, formed by the top and band folds and the covering 95 tape, provide a strong, rigid structure tending to hold the band erect, and permanently to induce a fold line in the top of the collars near the edge of the band, thus tending to prevent local sagging or crumpling of the 100 collar when it is on the neck of the wearer, and insuring a seemly hang of the fold-over top.

The above described construction enables a slightly or "dressy" soft fold-over collar to 105 be made with economy.

What I claim and desire to secure by Letters Patent is:

1. A fold-over collar having a band and a top, each being a single piece of heavy 110

self-sustaining fabric of uniform flexibility throughout, and a covering tape, the band being edge-folded on itself, the raw edge of the top being turned to overlie the folded edge of the band, the covering tape overlying the turned edge of the top and overlapping the turned edges of both top and band, and stitched to the band body directly along a line adjacent to the inturned edge parts of both band and top, and to the band and top along a line adjacent to the fold of the top, the heavy inturned, conjoined and over-taped juncture between band and top forming a relatively rigid structure inducing a fold in the top near the edge of the band.

2. A collar having a band and a top, of each of which the principal extent is comprised of a uniform single thickness of woven textile fabric, sufficiently thick and stiff to be inherently self-sustaining, band and top being conjoined, the juncture comprising overlapped portions constituting multiple layers of said fabric of uniform thickness conjoined in a relatively rigid structure predetermining a fold line in the adjacent uniform fabric of the top.

3. A fold-over collar, having a top piece

and a band piece having a fold at its top edge separately shaped from heavy material of uniform flexibility throughout, and conjoined in a seam involving layers of the respective pieces lying parallel with and near the folded top edge of the band, the structure including a covering tape for the seam overlying said folds, whereby the band tends to remain flat, and the top to fold over adjacent the said seam.

4. A fold-over collar, having a top piece and a band piece having a fold at its top edge separately shaped from single thicknesses of like, heavy material of uniform thickness and pliability, said top and band being conjoined in a seam involving layers of the respective pieces lying parallel with and near the folded top edge of the band, the structure including a covering tape for the seam overlying said folds, and stitching holding the elements of the seam in place, whereby the band tends to remain flat, and the top to fold over adjacent the said seam.

Signed by me at Kitchener, Ontario, this sixth day of June, 1921.

JOHN WILLIAM HESS.
